UNITED STATES PATENT OFFICE.

DANA ESTES, OF BROOKLINE, MASSACHUSETTS.

FIRE EXTINGUISHER.

Application filed December 7, 1922. Serial No. 605,384.

This invention relates to improvements in fire extinguishers. More particularly it relates to the soda or other alkali and acid type of portable extinguishers and to the means for separating the soda and acid until the proper time for mixing them, and for then mixing them at a proper rate and under control.

In apparatus of this type it is desired to 10 keep acid, preferably sulphuric, in a bottle in the top of a canister nearly filled with a solution of an alkali, preferably bi-carbonate of soda. Numerous mechanical arrangements and devices have been proposed, all 15 involving the same fundamental principle for keeping the two apart until needed. The necessity that the elements be unfailingly brought together when needed led to the general abandonment of acid containers that 20 require to be crushed, and to the use, either of those having a loose cover, which falls away by gravity, or one removable by exterior application of mechanical force.

To this end lead has been used for the closure, but this is subject to slow attack by the acid, making lead sulphate, which in some cases causes the stopper to adhere to the bottle or to its connection so that the apparatus is inoperative at the critical time of 25 need. Glass cannot be used, because it is too brittle and because of the tendency of the liquid to creep over its surface in the presence of any salts which may be formed until contact is established, and the power of the 30 contents thereby gradually weakened. Porcelain also has been used, and is most commonly in use today; but this also is an unsatisfactory material, because it has a surface which although better than glass nevertheless does not always prevent the creeping 35 of liquids, especially where there are temperature changes that cause condensation, and moreover it has to be made thick for safety against mechanical breakage in 40 parts that preferably would be of small dimension in order to get accuracy of control of the acid flow; and it cannot be made with high precision of dimension because of distortion which it undergoes in its firing. 45 Nothing really suitable having heretofore been within the range of existing knowledge and skill, as those skilled in the art have long well known, the present invention is a discovery of that thing.

It consists in making the stopper of the 55 acid bottle of steatite. Steatite is a mineral product which has long been well known in the art and industries, being for example the material from which the tips of domestic gas burners are made, from which tips the gas 60 issues to the flame, known as "lava" tips, and being widely known also as an electrical insulator. The properties which are important in the uses to which it is put in those instances cited are of no especial consequence 65 in the present case; but the material has also the property that sulphuric acid has no effect whatever upon it. It is unlike lead in this respect; and it is unlike porcelain in that the liquids do not creep over its surface. It has 70 sufficient mechanical strength, even in small dimensions; and it can be worked like metal to precise dimensions with tools, while soft, and does not lose its precision when hardened.

As applied to the purposes of the present invention, steatite, an earthy material having the chemical formula $H_2Mg_3Si_4O_{12}$ may be used, which is the general formula of talc. This may be worked like metal, to the required dimensions, with metal cutting tools, while in the state in which it is found in nature, and then may be hardened by methods already well known, including a baking or 75 burning in a kiln, somewhat as with porcelain, where coal or coke ovens are used, or with electric or gas blast furnace. The product thus made is not affected by alkali or sulphuric acid; has no glaze; is about equal to granite, glass and marble in 80 specific gravity; and is so hard that a diamond is required to cut it. In compressive strength it has double that of granite, and several times that of marble and brick. It 85 therefore has ample strength for the purpose 90 of the invention; but as a precautionary measure against brittleness until there shall have been a greater experience in its use I propose to reinforce it with a core, which if not of non-corroding material, may be of 95 slow corroding material having sufficient tenacity, such as lead, arranged so as not to touch any surface to which its corrosion 100 might cause adhesion.

The core may be secured in the stopper by 105 heading over the ends of the core, or by a screw threading it into the material of the stopper or otherwise.

The accompanying drawings represent embodiments of the invention such as may be used in various types of fire extinguishers; and it will be understood that the invention 5 may be employed in other forms as well. It is intended that the patent shall cover by suitable expression in the appended claims whatever features of patentable novelty exist in the invention disclosed.

- 10 In the accompanying drawings, Figure 1 is an elevation in medial section, of one end of a fire extinguisher of the type described, inverted as for use and containing a stopper embodying the invention, showing its setting 15 and surroundings when in use.

Figure 2 shows a similar stopper of solid steatite.

Figure 3 shows a stopper adapted for an extinguisher of the so-called sealed bottle 20 type, in which the extinguisher would hold the stopper mechanically in contact with the mouth of the acid bottle in such a way as to render the said bottle practically acid tight, with provision for the withdrawal of 25 the stopper by force when wanted for use.

Figure 4 is a modification, suitable for the same use, with a different core attachment and with reinforced head flange.

Figure 5 is another modification suitable 30 for the same use, wherein the core is not exposed to the acid; and

Figure 6 is another modification, with smooth core.

In the drawings 10 indicates the canister 35 of a soda and acid fire extinguisher, being a copper shell, represented as when turned upside down for use. The screw cover 11 is therefore at the bottom, and the can has tight closure except for the discharge opening 12 where the liquid contents are forced out through a hose 13 under pressure of gas generated gradually within as acid from the inverted bottle 14 flows out through its neck into contact with the soda solution. The 40 bottle, being supported on the metal shell 14', its mouth is at a carefully predetermined height above the cap 11 on which the stopper also is supported. As the protuberance 45 is conical, the dimension of the annular opening depends upon the relation of the stopper to it in size and position; and on this dimension of annular opening depends the rate of flow of the acid into the annular cup 16 in the stopper, to which soda 50 solution enters freely and from which the gas generated escapes producing the pressure that forces out the soda solution to discharge, 12, 13. The present invention does not reside in the said shape or operation 55 of the stopper, but in the construction and material above described, steatite, with 60 65

or without a core. The modifications illustrated in Figures 1-6 show sundry shapes in which the stoppers of the invention may be made. While experience thus far has indicated that a stopper of solid steatite is 70 adequate for its purpose, without a core, the drawing illustrates several arrangements in which a core may be combined with it in order to prevent fracture of the stopper and to hold together pieces thereof in case a 75 fracture occurs.

In Figure 1 the core 17 consists of a smooth rod of material, suitably acid resistant, such as lead or a lead alloy, set in a smooth hole drilled through the steatite, 80 and this is securely retained in place by heading over its ends as at 18. It will be noticed that although the core is exposed to fumes of the acid, when the bottle is upright and ready for action, it nevertheless 85 does not make contact at any place with the bottle; and therefore the products of its corrosion cannot cause adhesion of the stopper to the bottle. On the other hand, its head, which is downward in Figure 1, 90 is the part of the stopper which makes contact with the cap when the canister is inverted, so that the blow in falling open is received on the lead rather than directly on the steatite.

In Figure 2 a similar form of stopper is employed in which there is no core of other material. Reliance is placed on the strength of the steatite alone.

Figure 3 shows a stopper with core 17 as 100 in Figure 1, but the stopper's body of steatite has a neck 19 and a flange 20 at its head. This neck 19 may be embraced mechanically by a suitable device (not shown), several types of which are well known, for pushing 105 the stopper toward or withdrawing the stopper from the bottle neck at will, by pushing on its body 30 or pulling on its flange 20, instead of letting the stopper fall away by gravity.

Figure 4 illustrates a similar stopper, and shows how a stout metallic disk 21 which in this case is integral with the core 17^a may overly the head flange of the steatite and strengthen it for responding to any pull 115 tending to open the bottle. The core 17^a is screwed into the stopper and therefore is engaged at all parts of its length.

Figure 5 illustrates the provision of screw threads 22 on the head of the stopper, as 120 a means for engaging the stopper to withdraw it by externally applied force, from the bottle neck, and also illustrates at 23 how the inner face of the stopper may be continuously of the acid resisting steatite 125 without penetration by the core, yet have the core present. In this case the core may be made of any desired material, not being exposed to the acid fumes. This is accomplished by drilling and tapping the top of 130

the core as at 17^a, but stopping short of complete penetration, along the axis of the stopper. It will be understood that, unlike porcelain, internal threads in the stopper are 5 practicable with great precision.

Figure 6 illustrates a stopper with a tip adapted to enter the bottle neck as in Figure 1, and to remain somewhat within the neck, when withdrawn to varying degrees 10 by apparatus, not shown, screwed on the threads 22 at its head end. In this case the flow can be graduated to a nicety by the degree to which the stopper is withdrawn; and the core 17 protects the tip portion of the 15 stopper.

The method of manufacture of the described stoppers is that which is common in the manufacture of materials from steatite, commonly called "lava" in the trade; and 20 the core may be inserted afterward. This involves the cutting of the stopper to its desired shape with tools such as are used in metal work, cutting any threads that may be desired, by this means, and then treating 25 and burning it in a manner already known, and afterwards inserting the core, if there is to be a core. The accuracy of dimensioning of which the material steatite is capable, the strength and hardness of the same after 30 burning, the freedom of the material from absorption, accumulation and creeping of liquid, and from attack by acid, make the stoppers made of it superior to any others known in the art.

35 The invention thus described may be applied in other ways, both as regards the bottle and as regards the stopper, which together are necessary in order to make a complete separation of alkali from acid. In extinguishers of the sealed bottle type accuracy of fit of the stopper is very important. The gaskets customarily employed for attaining such a fit are liable to stick and to 40 corrode. The steatite can be ground so as 45 to make a tight fit without a gasket. Thus a tight fit can be made in a glass bottle.

The utility of the stopper core above described is not limited to steatite. The core may be provided in a stopper of other material, so that even with a material more brittle than is steatite, if a fracture occurs the core will hold the stopper together so that the pieces into which it may be broken will not fall apart and lodge in such a way as to 50 interfere with the outflow of acid when the fire extinguisher is wanted for use.

I claim as my invention:

1. In a fire extinguisher having acid in a container associated with alkali in a larger container, means separating the acid from 60 the alkali while the first mentioned container is in acid holding position, comprising a body having a steatite surface.

2. In a fire extinguisher having acid in a container associated with alkali in a larger 65 container, means separating the acid from the alkali, while the first mentioned container is in acid holding position, comprising a body of steatite having a core of tenacious material so shaped as to embrace parts 70 of the steatite body.

3. In a fire extinguisher having acid in a container associated with alkali in a larger container, means separating the acid from 75 the alkali, while the first mentioned container is in acid holding position, comprising a body of steatite having a core of a kind of metal which is slightly corrodible by the acid, said core being arranged so as not to touch the acid container. 80

4. In a fire extinguisher having acid in a container associated with alkali in a larger container, means separating the acid from the alkali, while the first mentioned container is in acid holding position, comprising 85 a body of steatite, there being a screw threaded hole formed centrally in the steatite, and a metallic core screwed therein.

5. In a fire extinguisher having acid in a container associated with alkali in a larger 90 container, means separating the acid from the alkali, while the first mentioned container is in acid holding position, comprising a body of steatite; comprising a stopper having a neck, and a head larger than the 95 neck whereby it may be withdrawn and a metallic re-enforcement for the steatite comprising a disk overlying said head, and a core attached to said disk and set within the said body and engaging said body. 100

6. A fire extinguisher comprising the combination, with a container for alkali, of a bottle of acid and means to support it therein, and a stopper of steatite arranged to close the bottle when upright and to fall 105 away from it when the bottle and stopper are inverted, thereby permitting the acid to flow out into the alkali.

Signed at Boston, Mass., this fifth day of December, 1922.
